(57) **CLAIM**

The ornamental design for a bar for vehicle rack, as shown and described.

DESCRIPTION

FIG. 1 is a front, top, and left side isometric view of the first embodiment of a bar for vehicle rack showing the new design;

FIG. 2 is a rear, bottom, and right side isometric view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof, enlarged by a factor of three;

FIG. 8 is a rear elevation view thereof, enlarged by a factor of three;

FIG. 9 is a front, top, and left side isometric view of the second embodiment of a bar for vehicle rack showing the new design;

FIG. 10 is a rear, bottom, and right side isometric view thereof;

FIG. 11 is a top plan view thereof;

FIG. 12 is a bottom plan view thereof;

FIG. 13 is a left side elevation view thereof;

FIG. 14 is a right side elevation view thereof;

FIG. 15 is a front elevation view thereof, enlarged by a factor of three; and,

FIG. 16 is a rear elevation view thereof, enlarged by a factor of three.

The dashed lines and the structures they depict are shown for the purpose of illustrating environmental subject matter and form no part of the claimed design. In FIGS. 9 through 14, the break lines in the drawings of the second embodiment indicate that any portion between the break lines forms no part of the claimed design. All other views of the bar for vehicle rack are the same as those in FIGS. 1 through 8 with
